Samuel W. Hudson.

UNITED STATES PATENT OFFICE.

SAMUEL W. HUDSON, OF HUDSONDALE, PENNSYLVANIA.

RAILROAD-TRACK.

SPECIFICATION forming part of Letters Patent No. 310,281, dated January 6, 1885.

Application filed July 1, 1884. (No model.)

To all whom it may concern:

Be it known that I, SAMUEL W. HUDSON, of Hudsondale, Carbon county, Pennsylvania, have invented certain new and useful Improvements in Railroad-Tracks, of which the following is a specification.

In the ordinary railroad-track the rails are laid on ties or sleepers placed at regular intervals apart. This arrangement affords the same or an equal amount of support to all parts of the rails. It is found, however, that greater firmness is needed at the junction of the rails, as the track is liable to sink or give at this point.

My invention consists in remedying this defect by providing additional supports for the rails at their junction.

The accompanying drawing is a plan view of a railroad-track embodying my improvements. The rails A are laid on ties B, which are of the ordinary size, and are placed at regular intervals apart. At X the long tie B extends under the junction of the rails A. A. On each side of the tie B are placed short sleepers or sections of ties, C, to which the rails are secured in the same manner as they are to the long tie. A firm bed is thus made for the rails at this point and the track is kept uniformly even. At Y the junction of the rails is shown as being midway between the long ties, and

a short sleeper or tie-section, C, is located underit. This construction gives equally good results, and either or both of the methods may be employed in laying a track.

The track may be re-enforced at other points than at the junction of the rails, as indicated at Z. I may with advantage use sections of rails the ends of which have worn out or rotted away, and thus, without materially increasing the expense, greatly improve the track. I do not however claim, broadly, the use of short tie-sections in connection with long ties, nor, broadly, the use of supplemental supports between the long ties.

I claim as my invention—

1. The combination, substantially as set forth, of the rails, the long ties, and the short tie-sections that re-enforce the track at the junction of the rails.

2. The combination, substantially as set forth, of the rails, the long tie placed under the junction of the rails, and the short tie-sections placed under the rails on each side of the long tie.

In testimony whereof I have hereunto subscribed my name.

SAMUEL W. HUDSON.
